(74) *Attorney, Agent, or Firm*—Leydig, Voit & Mayer, Ltd.

(57) **CLAIM**

The ornamental design for a broom block, as shown and described.

DESCRIPTION

FIG. 1 is a rear perspective view of a first embodiment of a broom block according to the present invention;

FIG. 2 is a top view of the broom block of FIG. 1;

FIG. 3 is a bottom view of the broom block of FIG. 1;

FIG. 4 is a side view of the broom block of FIG. 1;

FIG. 5 is a side view of the other side of the broom block of FIG. 1;

FIG. 6 is a front view of the broom block of FIG. 1;

FIG. 7 is a rear view of the broom block of FIG. 1;

FIG. 8 is a rear perspective view of a second embodiment of a broom block according to the present invention;

FIG. 9 is a top view of the broom block of FIG. 8;

FIG. 10 is a bottom view of the broom block of FIG. 8;

FIG. 11 is a side view of the broom block of FIG. 8;

FIG. 12 is a side view of the other side of the broom block of FIG. 8;

FIG. 13 is a front view of the broom block of FIG. 8; and,

FIG. 14 is a rear view of the broom block of FIG. 8.

The broken lines shown in the drawings are for environmental purposes only and form no part of the claimed design.
